SMOKING PIPE

Peter Gustafson, Chicago, Ill.

Application July 20, 1948, Serial No. 39,620

3 Claims. (Cl. 131—184)

1

The present invention relates to smoking pipes, and this disclosure comprises an improvement over the smoking pipe disclosed and claimed in my copending application, Serial No. 39,619, filed July 20, 1948.

In the other application it is pointed out that the long existing problem of preventing the formation of tars and nicotine-containing residues in the smoke passages of a pipe can successfully be solved by the utilization of a ventilating pump, manufactured as an integral part of the pipe and arranged to force air through the smoke passages of the pipe to eject the liquid condensate therefrom before the condensate is allowed to evaporate and form sticky or gummy residues.

It is the specific object of the present invention to provide an improved smoking pipe, of the general style disclosed in the above identified application, but so designed and constructed as to permit the reciprocating plunger of the pump to rest in its innermost position in the pump cylinder during smoking, yet to be in a position wherein it is effective to force air through the smoke passages and ventilate said passages on its first stroke; so that initial movement of the pump plunger does not draw vapors from the smoke passages into the pump cylinder. In this connection, it may be explained that in order to keep the interior passages of the pipe entirely free of residues, it is desirable to avoid any possibility of drawing even a small amount of smoke, or liquid condensate, from the smoke passages into the cylinder of the pump. This is avoided in my other disclosure by keeping the piston rod in its withdrawn position during smoking, so that the piston is normally at rest at the beginning of its stroke, but in certain styles of pipes this is disadvantageous; and it is accordingly the object of the present invention to provide a means whereby the piston may be reciprocated without drawing vapor or air from the smoke passage into the cylinder, but will effectively force air through the smoke passages in unidirectional flow, to eject any vapor and condensate from the passages.

The present preferred embodiment of the invention is illustrated in the drawings attached to and forming a part of this specification, wherein:

Figure 1 is a central sectional view of a smoking pipe constructed in accordance with these teachings;

Figure 2 is an enlarged detail sectional view of the air pump, as contemplated by this invention,

with the piston at a position intermediate the ends of its stroke; and

Figure 3 is a detail sectional view taken substantially on the plane of the line 3—3 of Figure 2.

The pipe includes a bowl 10 and stem 11 with a mouthpiece 12, in which a hollow metal tube 14 is mounted. The tube supports the mouthpiece and extends through a bore in the stem to a point under the bowl 10. The tube 14 is perforated at 15 to provide an orifice to communicate with the bottom opening 16 of the bowl, so that smoke from the burning tobacco may be drawn through the tube and out through the channel 17 of the mouthpiece. The tube extends beyond the opening 16, however, and is provided near its extreme end with another opening 18 which serves as an air port adapted to communicate with an air passage 19 from the end of a small pump cylinder 21, in which a piston 22 is slidably mounted. The end of the pump cylinder is closed in any convenient manner, as by a plug 23, and a slide rod 24 and knurled knob 25 are provided so that the piston 22 may be manually manipulated to force air from the pump cylinder through the tube 14 and orifice 15 of the stem on its inward stroke, and to draw fresh air into the pump cylinder on the return stroke. The slide rod 24 extends through an aperture 23a of the plug 23. The plug 23 may be loosely fitted on the rod 24 so that air may flow through the aperture in the plug as the pump is operated.

It will be noted when the pipe is in the normal smoking position, illustrated in Figure 1, the opening 18 is closed by the wall of the bowl, so that no condensate will accumulate in the pump cylinder, yet the orifice 15 in the tube is unobstructed to complete a smoke passageway from the pipe bowl 10 through the tube 14 in the stem and through the channel 17 in the mouthpiece 12. By rotating the mouthpiece 12 a quarter turn, the orifice 15 may be closed off and the air port 18 of the tube brought into communication with the air passage 19 of the pump, so that the interior of the tube 14 and channel 17 of the mouthpiece are in unobstructed communication with the pump cylinder 21.

The rod 24 is of substantial diameter and is provided with a central bore 26, extending completely through from the piston 22 to the end of the knob 25 to provide unrestricted air communication between the inside of the cylinder 21 and the atmosphere. The bore 26 is larger in diameter than the bore of the smoke tube 14 and the channel bore 17 of the mouthpiece, and is

also much shorter; so that the resistance to air flowing through the bore 26 is far less than the combined resistance of the channel 17 and tube 14. Thus, in operation, when the knob 25 is withdrawn to move the piston 22 outwardly, the initial flow of air to fill the cylinder of the pump will be drawn inwardly through the bore 26 into the cylinder, rather than through the smoke passages. In effecting the return stroke, the operator will move the piston inwardly by placing the end of his finger on the knob 25 and pressing it in. This will effectively close the outer end of the bore 26 during the full stroke, so that, as the piston 22 and knob 25 are moved inwardly, the air from the cylinder 21 will be forced outwardly from the pump cylinder through the tube 14 and the channel 17. The movement of air through the smoke tube and mouthpiece will eject liquid condensate therein, and effectively clear the smoke passages of smoke or lingering vapor.

The air capacity of the cylinder 21 should be somewhat greater than the entire volume of the smoke passage between the orifice 15 and the end of the mouthpiece, so that all of the condensate and smoke residues or vapors may be ejected in a single stroke. It is understood, of course, that subsequent strokes may be desirable for the purpose of further ventilating the smoke passage and drying its interior surfaces, but in any event the manipulation of the piston in the manner indicated effects a flow of air through the smoke passages, so that there is no possibility of any residues or vapors being drawn into the pump cylinder.

It should be apparent from the foregoing description that the teachings from this invention provide a specific combination and arrangement of parts adapted to move fresh air through the smoke passages of a smoking pipe, so that the passages may be maintained in a clean, fresh and sanitary condition, and at the same time so arranged to effectively prevent the possibility of residues accumulating in the cylinder pump. The several parts of the pipe are so related that the assembly may be of neat, compact and streamlined appearance, yet incorporate the mechanical features necessary to accomplish the desired results.

Having thus described the invention, what I claim as new and desire to protect by United States Letters Patent is:

1. A smoking pipe having, in combination, a tobacco bowl, a mouthpiece, a smoke passage means between the bowl and the mouthpiece, and an air pump integral with, and below said bowl, and parallel with said smoke passage means, said pump having a hollow piston rod, a longitudinally movable piston carried at the inner end of the hollow rod, the bore of the hollow piston rod being located between the pump cylinder and the atmosphere, and an opening comprising an air passage at one end of the pump cylinder communicating with a coinciding opening in said smoke passage means comprising an air port whereby air may be caused to flow unrestrictedly into the cylinder during outward movement of the piston and the bore may be manually closed during inward movement to afford air circulation through the smoke passages of the pipe by the action of said pump.

2. A smoking pipe comprising, a tobacco bowl and an integral stem wherein an opening in said bowl communicates with a bore in said stem, a channeled mouthpiece rotatable on the end of

5 said stem, a tube secured to said mouthpiece and extending into said stem bore to a point beyond said bowl opening, said tube having a circumferentially and axially spaced orifice and air port, 10 said orifice being positioned for either registering with said bowl opening or being sealed by the bottom portion of the bowl when rotated out of registry with the opening therein, a pump cylinder below said bowl having an air passage registerable with said tube air port when said tube orifice is sealed by the bottom portion of said bowl, a piston in said cylinder, a tubular piston rod extending outwardly through the head of said cylinder and terminating in a manually operable head through which the bore in said piston rod communicates with the ambient atmosphere, said bore being adapted to be closed by a finger of the operator during the inward stroke of the piston for forcing a portion of the air in said cylinder and rod outwardly through the bore in said stem and the channel in said mouthpiece when said air port and air passage are in registration.

3. A smoking pipe comprising, a tobacco bowl and an integral stem wherein an opening in said bowl communicates with a bore in said stem, a channeled mouthpiece rotatable on the end of said stem, a tube secured to said mouthpiece and extending into said stem bore to a point beyond 25 said bowl opening, said tube having circumferentially and axially spaced orifice and air port, said orifice being positioned for either registering with said bowl opening or being sealed by the bottom portion of the bowl when rotated out of 30 registry with the opening therein, a pump cylinder below said bowl having an air passage registerable with said tube air port when said tube orifice is closed by the bottom portion of said bowl, a piston in said cylinder, a tubular piston rod extending outwardly through the head of said cylinder and terminating in a manually operable head through which the bore in said piston rod communicates with the ambient atmosphere, said bore being adapted to be closed by a finger of the operator during the inward 35 stroke of the piston for forcing a portion of the air in said cylinder and rod outwardly through the bore in said stem and the channel in said mouthpiece when said air port and air passage are in registration, the diameter of said tubular piston rod being greater than the diameter of the bore of said bowl and the channel of said mouthpiece.
